UNITED STATES PATENT OFFICE.

CHRISTIAN KECK, OF CRESCENT SPRINGS, KENTUCKY, ASSIGNOR TO THE GLOBE-WERNICKE COMPANY, OF CINCINNATI, OHIO, A CORPORATION OF OHIO.

CARD-FILE.

SPECIFICATION forming part of Letters Patent No. 735,112, dated August 4, 1903.

Application filed December 10, 1902. Serial No. 134,638. (No model.)

To all whom it may concern:

Be it known that I, CHRISTIAN KECK, a citizen of the United States, residing at Crescent Springs, in the county of Kenton and State of Kentucky, have invented certain new and useful Improvements in Card-Files, of which the following is a full, clear, and exact description, reference being had to the accompanying drawings, forming part of this specification.

10 My invention relates to files for index or other cards for use in libraries, offices, and other places where cards are used for purposes of indexing accounts or reference; and it has for its object the improved construction 15 of such files whereby their ease of manipulation, security, and efficiency are increased.

The novelty of my invention will be hereinafter more fully set forth and specifically pointed out in the claims.

20 In the accompanying drawings, Figure 1, Sheet 1, is a plan view of a card-file embodying my invention. Fig. 2, Sheet 1, is a central sectional side elevation of the same. Fig. 3, Sheet 2, is an enlarged elevation, partly in section, showing the operating mechanism when the card-retaining rods are closed and with the end of the drawer removed. Fig. 4, Sheet 2, is a corresponding view showing the card-retaining rods spread apart and the position of 25 the operating parts under this adjustment. Fig. 5, Sheet 2, is a detail sectional side elevation of the lower part of the follower and its parts which engage the card-retaining rods. Fig. 6, Sheet 2, is a plan view of the 30 card-retaining rods and the pivoted latch therefor which is carried by the follower. Fig. 7, Sheet 2, is a perspective view of the card-retaining rods at one end when closed. Fig. 8, Sheet 2, is a view corresponding to Fig. 40 7, showing the rods spread apart.

The same letters of reference are used to indicate identical parts in all the figures.

In its preferred form of construction the file is a drawer, of which a series is usually employed and contained in a suitable case or cabinet. The drawer may have an interior width just sufficient to contain a single row of cards which stand on edge transversely of the drawer, or it may be wide enough to have 45 50 two or more card-compartments side by side

and extending from the front to the rear of the drawer. I have only illustrated a drawer with a single card-compartment; but it will be readily understood that this may be duplicated or pluralized into a drawer with any 55 number of compartments desired, the mechanism in each compartment being identical with that illustrated and to be described.

In the drawings, A represents the bottom of the drawer; B, its side walls; C, its front wall, and D its rear wall. There is a slot E through the bottom of the drawer at its middle extending its entire length for the passage of the bottom lug or foot-piece of the sliding follower F, to be hereinafter described. Secured to the inner side of the front and rear walls at their middle and extending to the bottom are two guide and housing plates G, similar in construction and clearly shown in Figs. 1, 2, 3, and 4. These 60 plates contain a bent-out inwardly-projecting portion forming on the rear of each a horizontal slot a, at the middle of which is an opening b through the plate, and directly below this opening is a bent-out inwardly-projecting portion c, Figs. 3 and 4, forming a 65 housing for crank-arms d, fast on a horizontal rod H, extending the entire length of the drawer parallel with its bottom and journaled in the plates G, with a washer e at its 70 rear end, as seen in Fig. 2, and extending through the front wall C of the drawer and having an operating thumb-button f upon the exterior of the front wall of the drawer, which button serves not only to turn the rod 75 80 85 H on its axis to spread and draw together the filing-rods, but also serves to pull out and push in the drawer in its compartment.

Just above rod H are the two parallel card retaining and releasing rods I, which are flat 90 bars standing vertically and having their ends g, Figs. 3, 4, 7, and 8, bent at right angles and secured in the slots a of the housing-plates G, the bars themselves passing through the openings b in said plates. The lower 95 sides of the arms g are beveled off from their angle to their outer extremities, as clearly seen in Fig. 4, for a purpose to be presently explained, and links h connect the opposite ends of the crank-arms d with the outer ends 100

of the arms *g*, as seen in Fig. 4. These links are rigid pieces and have pivotal connections both with the crank-arms and the arms *g*.

In Fig. 3 the position of the parts is shown 5 with the bars *I* drawn together, in which position they are slightly tilted from each other at their upper edges, and the arms *g* rest upon the bottom of the slot *a*. This is the position they occupy when it is desired to re-
10 move one or more cards from the drawer or to replace the same, the cards having in their lower edges the usual vertical slot terminating in an upper oval opening to permit the spreading of the bars when the cards are to be locked in the drawer, as is common in this class of card-files.

To spread the bars *I* to lock the cards within the drawer, as seen in Figs. 4 and 8, it is only necessary to turn the button *f* and partially rotate the rod *H* to the position shown 20 in Fig. 4, when the bars will first be thrown to a vertical position, as seen in Fig. 7, with the upper edges of the arms *g* resting against the upper sides of the slots *a*, and then they 25 will be drawn uniformly and bodily away from each other, always maintaining their parallel position, as seen in Figs. 4 and 8.

The follower *F* is of the usual or any suitable construction, having a lower portion occupying 30 a space in the slot *E* and with an aperture through the same for the passage of the rod *H*, which is held in frictional contact with the follower by any suitable spring, as *i*, Fig. 5. The follower likewise carries a 35 pivoted latch-piece *J*, Figs. 5 and 6, pivoted, as at *j*, with a beveled tongue *k*, adapted to drop down between the bars *I* when the latter are opened, as shown by the dotted lines, Fig. 5, thereby acting as a wedge to prevent 40 the pressing together of the bars *I* to enable any card or cards to be removed at the pinched-together portions while said bars are spread apart at their ends, as will be readily understood. This last-described device is especially 45 intended for use where the rod *H* has locking means for holding it in either of its turned positions, so that in case a file of cards was withdrawn from the cabinet and placed upon a table with the bars *I* spread apart to 50 lock the cards no one but the person authorized to operate the filing mechanism could pinch the bars together to remove and re-

place any one or more cards. As soon, however, as the rod *H* is turned to bring the bars *I* together said bars are first tilted by the 55 lowering of the arm *g* and are then drawn together in this tilted position and acting upon the beveled end of the tongue *K* of the latch *J* force the same upward and out from between the bars, which are then free to close 60 under and the latch-piece assumes the position shown by the solid lines of Fig. 5.

Having thus fully described my invention, I claim—

1. In a card-file, the combination of a filing-base, a pair of card retaining and releasing rods parallel therewith and having their ends bent outward and confined in guide-slots at the front and rear of the base, a rotatable rod suitably journaled below and parallel to said card-rods, crank-arms fast on said rotatable rod, pivoted links connecting said crank-arms and the bent-out ends of the card-rods, and an operating-button upon the end of said rotatable rod, substantially as described. 75

2. In a card-file, the combination of a filing-base, a pair of card retaining and releasing rods parallel therewith, composed of flat bars set on end and having their ends bent outward and confined in guide-slots at the front 80 and rear of the base, said bent arms being beveled to permit a slight tilting motion of the card-rods, a rotatable rod suitably journaled below and parallel to said card-rods, crank-arms fast on said rotatable rod, pivot- 85 ed links connecting said crank-arms and the bent-out ends of the card-rods, and an operating-button upon the end of said rotatable rod, substantially as described.

3. In a card-file, the combination of a filing-base, a pair of card retaining and releasing rods parallel therewith, composed of flat bars set on edge, mechanism for slightly tilting and bodily moving said bars toward and from each other, and a follower mounted on the 95 base and provided with a latch-piece adapted to drop between the card-bars when spread apart and to be automatically raised from between said bars when the latter are drawn together, substantially as described.

CHRISTIAN KECK.
